REEL FOR STRING

Jerry A. Brinkman, 635 Alameda Place,
Dayton, Ohio 45405

Filed Apr. 19, 1971, Ser. No. 135,535

Term of patent 7 years

Int. Cl. D8—05

U.S. Cl. D8—222

FIG. 1

FIG. 2

FIG. 3

FIG. 4

FIG. 1 is a top perspective view of the reel for string, showing my new design;

FIG. 2 is a top plan view thereof;

FIG. 3 is a side elevation view thereof, taken from the bottom of FIG. 2; and

FIG. 4 is an end view thereof.

I claim:

The ornamental design for a reel for string, as shown.
